UNITED STATES PATENT OFFICE.

SAMUEL GEOGHEGAN, OF KILLINEY, IRELAND.

CAR-COUPLING.

SPECIFICATION forming part of Letters Patent No. 660,503, dated October 23, 1900.

Application filed March 12, 1900. Serial No. 8,334. (No model.)

To all whom it may concern:

Be it known that I, SAMUEL GEOGHEGAN, a subject of the Queen of Great Britain and Ireland, residing at Killiney, county of Dublin, 5 Ireland, have invented Improvements in a Combined Coupling, Buffing, and Draw-Gear Apparatus for Railway or Similar Vehicles, of which the following is a specification.

This invention has reference to improvements in that class of combined coupling, buffing, and draw-gear apparatus for railway and similar vehicles that is capable of angular movement in various directions on the vehicle to which it is applied, as when 15 passing around curves and during coupling, and which will admit of two vehicles provided with such apparatus being readily coupled not only when on straight portions of track, but also when one or both of them is or are on 20 a curve and when the axes of the two buffer and draw bars on their respective vehicles are at different heights.

The objects of the invention are to effect the 25 secure coupling of vehicles, and also it may be their train-pipes, automatically, so that when engaged they will constitute one or more rigid connections which shall be so proportioned as regards length of buffer-rod that even for long double bogie-vehicles the ends 30 of the couplings can pull from a point so near the center of the vehicle that under no ordinary circumstances would there be any chance of derailment or undue strain caused by the center line of the couplings being at 35 too acute an angle to the center line of either vehicle; to avoid the objectionable rubbing action between the buffers, such as occurs with the ordinary buffers of vehicles used on main lines; to provide a coupling which will 40 be suitable for vehicles traveling on curves down to a radius of six times the gage of the line; to have a secure and tight coupling without the aid of tightening apparatus; to provide a coupling which will couple automatically 45 on the smallest possible curves and the greatest usual differences of level in the couplings, and to provide a coupling which can be uncoupled, left uncoupled, or put in a position for recoupling from either side of 50 the vehicle.

According to this invention each combined buffer and draw-bar which is mounted to

move in an angular manner against the action of a spring, as heretofore, and is herein-after called for brevity the "buffer-rod," is 55 provided at its outer end with a buffer-head of appropriate shape and dimensions to suit the curves of the track over which the vehicles are to run and the differences of level between the axes of adjacent buffer- rods. 60 The smaller the radii of the curves and the greater the differences of level of the buffer-rods the wider and deeper will the buffer-heads be respectively made. The buffer-rod and head are provided with a pair or set of 65 horns or projections that extend in directions away from the end of the vehicle to which the apparatus is applied and diverge from each other in both vertical and lateral senses when in their normal or operative positions 70 and which are so constructed that they constitute combined centering and coupling devices, the arrangement being such that when two vehicles, the buffer-rods of which are provided with devices of the kind referred to, are 75 forced together portions of the devices carried by the buffer-rod of the one vehicle will become engaged with the buffer-head or with portions of the corresponding devices carried by the adjacent buffer-rod of the other vehicle, 80 so as to automatically couple the two vehicles together, and should the axes of the two buffer-rods previous to coupling be at an angle to one another or at different heights the buffer-heads and horns will coöperate with one another to 85 turn the said rods so as to bring them into line, after which the coupling portions of the horns will effect the coupling of the two vehicles, as before explained. For uncoupling the vehicles the horns of each set are by suitable means provided for the purpose and capable of being actuated from either side of the vehicle moved into an inoperative position—as, for example, by causing them to 90 turn backward about separate transverse axes 95 or in a transverse direction about a common longitudinal axis. To allow each buffer-rod to move in an angular direction, as described, it is or may be mounted to work endwise through two bearings between which one or more combined buffer and draw springs is or are interposed and one of which is made in the form of a sleeve that has a flared opening therethrough for the buffer-rod and works 100

endwise in a third bearing that is carried by the head-stock or underframe of the vehicle in such a manner that it can turn about a vertical axis, the other of the two first-mentioned bearings being connected to the third bearing in such a manner—as, for example, by bolts—that it can move endwise in either direction to a limited extent against or by the action of the combined buffer and draw spring or springs and can also move in an angular direction to a limited extent with the buffer-rod that passes through it.

According to my invention I sometimes combine with apparatus for coupling vehicles together means for simultaneously coupling pipes—such as those used for pressure and vacuum brakes, passenger and guard communication appliances, heating appliances, and the like—the arrangement being such that the act of coupling the vehicles will also effect the coupling of the pipe or pipes. In carrying out this part of my invention as applied in combination with vehicle-couplers such as hereinbefore referred to each buffer-rod according to one arrangement is made hollow and is connected at its inner end to one or more lengths of flexible pipe and at its outer end to one or more flexible coupling devices adapted to make a close joint with a similar or appropriate coupling device or devices on an adjacent vehicle when the two vehicles are coupled together. These pipe-coupling devices may be of any suitable construction, or a flexible pipe or flexible pipes may extend through and be carried by the two hollow buffer-rods of a vehicle and be fitted with coupling devices at its or their outer ends.

Combined coupling, buffing, and draw-gear apparatus according to this invention can be constructed and arranged in various forms.

In the accompanying illustrative drawings, Figure 1 is a front elevation; Fig. 2, a side elevation, partly in longitudinal vertical section; and Fig. 3, a plan showing one construction of combined coupling, buffing, and draw-gear apparatus according to this invention. Fig. 4 is a similar view to Fig. 2, but showing the coupling-horns in their inoperative positions. Fig. 5 is a front elevation, Fig. 6 a central longitudinal vertical section, and Fig. 7 a plan, showing another construction of my improved apparatus. Fig. 8 is a similar view to Fig. 5, showing some of the parts in their inoperative positions. Figs. 9, 10, and 11 show, respectively, in end elevation, side elevation, and plan part of a vehicle with a modified construction of coupling apparatus. Fig. 12 is a part plan showing a further modified construction. Figs. 13, 14, and 15 show detail views, hereinafter referred to.

As the combined apparatus at the respective ends of each vehicle in each arrangement are alike, it will be sufficient to describe only one apparatus of each arrangement.

Referring to Figs. 1 to 4, inclusive, *a* is the buffer-rod, formed with an outer enlarged end *b*, provided with two coupling and centering

horns *c*, that are, as shown, of outwardly-curved shape in plan and of curved or approximately-wedge shape in side elevation, the outer ends of the two horns diverging from each other and the inner ends thereof being arranged one above the other and fixed to separate spindles *d*, journaled in the enlarged outer end or head *b* of the said buffer-rod. *e* is a flat transverse plate fixed to and forming part of the buffer-head *b*. This plate is arranged with its flat sides vertical, and is hereinafter called, for distinction, the "buffer-plate." The two horns *c* are each recessed at *f* on the side next the buffer-plate *e*, so as to form hook-like parts or shoulders *g*. The spindles *d* upon which the horns are fixed are provided with crank-arms *h*, connected together by a coiled spring *k*, and one of the said spindles is connected to or forms part of a transverse rock-shaft *l*, the end portions of which are provided with handles *m* and extend through bearings *n*, which may be carried by the buffer-plate *e*. The inner ends of the horns *c* or the spindles *d* to which they are fixed are so connected together—as, for example, by toothed wheels or segments *o* or other gearing—that when one spindle and horn are partly rotated in one direction the other spindle and horn will be simultaneously rotated in the opposite direction. The arrangement is such that when the horns are in their normal or operative position they diverge from each other in an outward direction, and their recessed portions *f* are held against the top and bottom edges of the buffer-plate *e* by the coiled spring *k*, as shown in Fig. 2, and by partly turning the rock-shaft *l* in one direction the two horns will be caused to simultaneously turn backward about the axes of the spindles *d* into their inoperative positions, (shown in Fig. 4,) in which positions they will be held by the coiled spring *k*, which will by the partial rotation of the spindles *d* and crank-arms *h* have been moved to the opposite side of the plane containing the axes of the spindles to that at which it is located when it holds the horns in the operative positions, or the horns may be turned over when desired by lifting one by hand and depressing the other by foot. The buffer-rod *a* is arranged to slide endwise through, but not to rotate in, two bearings, the outer of which is in the form of a collar or plate *p*, against which the outer enlarged end *b* of the buffer-rod abuts and the inner of which is in the form of a sleeve *q*, that has an outwardly-flaring hole *r* therethrough and a flange *s* at its outer end. Against the inner end of the sleeve *q*, which is made convex, as seen in side elevation, Fig. 2, bears a washer or plate *t*, that is carried by the inner end of the buffer-rod *a* and is kept in place by nuts *v*, screwed on the said buffer-rod. The sleeve *q*, forming the inner or second bearing, is mounted to slide endwise, but not to rotate, in a third bearing or center-pin *w*, that may be a casting, the upper and lower ends

l of which are of circular shape and fitted to turn against the action of springs *x*, secured at one end to the said casting and at the other end to the head-stock of the vehicle about a vertical axis in holes 2 in bearings or plates 3, secured to top and bottom plates 4, forming part of or secured to the head-stock or under-frame of the vehicle. Between the inner bearing *q* and the outer bearing *p* and surrounding the buffer-rod *a* is a coiled spring 6, that serves both as a buffer-spring and as a draw-spring and is held in a compressed state by tie-bolts 7, that are jointed at one end to lateral pins 8 on the outer bearing *p* and at the other ends extend loosely through flanges *q* on the third bearing or center-pin *w* and are provided with T-heads 10 or equivalent, that normally bear against the said flanges and limit the outward movements of the outer bearing *p* and the spring 6, while leaving the said outer bearing free to be forced inward against the said spring.

Vehicles provided at each end with apparatus of the kind just described are coupled together by the coupling and centering horns *c* of each apparatus on the adjacent ends of two vehicles, slipping over and under and engaging with the buffer-plate *e* of the other and adjacent apparatus, as shown in full and dotted lines in Fig. 2, so as to securely lock the two vehicles together. When one or both of the vehicles is or are on a curve at the time of coupling and the two buffer-rods *a* are consequently at an angle to one another, those ends of the buffer-plates *e* on the two vehicles that are inside the curve, Fig. 3, will act against one another on that side of a line 12 (joining the vertical axes about which the two sets of apparatus turn) that is nearest the center of the curve, so as to cause the two buffer-rods *a* to be brought into line with each other, as seen in plan, the two sets of horns *c* acting to bring the two rods *a* into line, as seen in side elevation, if the rods *a* are at different heights previous to coupling. The length of the buffer-plates *e* is in every case so proportioned that the said plates will meet on the proper side of the line 12 12, as stated. To uncouple the vehicles, the horns *c c* of each apparatus are turned backward into the inoperative position shown in Fig. 4 by means of the rock-shaft *l*.

In the arrangement illustrated in Figs. 5 to 8, inclusive, the two horns *c* are formed in one with or fixed to the upper and lower portions of the buffer-head *b*, so as to project over and under the buffer-plate *e*, fixed thereto, and so as to diverge in outward lateral and upward and downward directions, and each of them is recessed at *f* near its inner end, so as to form a flat transversely-arranged surface or shoulder *g*, adapted to engage with the corresponding surface or shoulder on one or other of the horns *c* of similar apparatus on an adjacent vehicle. The combined horns *c*, buffer-head *b*, and buffer-rod *a*, which is of circular cross-section, are mounted to ro-

tate about a longitudinal axis and within inner and outer bearings *q* and *p*, respectively, of the kind hereinbefore described with reference to and shown in Figs. 1, 2, and 3, so that they can be moved into the operative position, Fig. 7, or into the inoperative position, Fig. 8, at will and be held in either of these positions by any suitable means. In the arrangement shown the said parts are adapted to be held in the operative or inoperative position at will by a pawl or catch 13, that is adapted (it may be under the action of a spring, but is not so shown) to enter one or other of two recesses 14 and 15 in the outer plate or bearing *p* and is connected to a transverse rock-shaft *l*, carried by the buffer-head *b*. The combined buffer and draw-spring 6 in this case is connected at its ends, which are bent for the purpose, to the inner and outer bearings *q* and *p*, respectively, so that during coupling the horns *c*, buffer-head *b*, rod *a*, and outer bearing *p* will be partly turned against the force of the said spring 6, which will react to hold the engaged horns *c* firmly together until the pawl or catch 13 on the buffer-head *b* is disengaged from the outer bearing-plate *p* to effect uncoupling of the horns and vehicles. In other respects the bearings *p* and *q*, center-pin *w*, and spring 6 are constructed and arranged as in the arrangement first herein described with reference to Figs. 1 to 4, inclusive.

The constructions of buffer-heads shown in the arrangements hereinbefore described are designed for use with vehicles intended to run over lines having curves of short radius. For ordinary railway-lines, the curves of which have a long radius, the buffer-heads can be made of much less width and of the ordinary circular shape, as seen in end view.

Figs. 9, 10, and 11 show an arrangement in which the buffer-head *b* is of ordinary circular shape, but provided with two oppositely-arranged combined centering and coupling horns *c* of the kind hereinbefore described, the said buffer-head and horns acting in the same manner as those hereinbefore described. In this example the buffer-head, with horns, is adapted to be rotated about the axis of the buffer rod *a* for the purpose of moving the centering and coupling horns into their inoperative positions by a flexible connector *b'*, that is connected at its ends to opposite parts of the buffer-head and is led around vertical guide-pulleys *b*² and under an operating-pulley *b*³, which is connected by links *b*⁴ to a transverse lever *b*⁵. When the buffer and horns are in their normal operative positions, the transverse lever is held in the horizontal position (shown in full lines in Fig. 9) by fixed supports *b*⁶, and when it is desired to move the horns into their inoperative position one or other end of the lever is disengaged from the corresponding support *b*⁶ and depressed, as indicated by dotted lines in Fig. 9, the opposite support *b*⁶ being at this time used as a fulcrum. If it be desired to hold the horns

in their inoperative position, the depressed end of the lever is engaged with the lower side of the corresponding support b^6 . The two ends of the flexible connector b' may be attached either directly to the buffer-head or, as shown, indirectly thereto through two bell-crank levers b^7 , that are adapted when the flexible connector is pulled by the depression of the lever b^5 to draw back two spring-pins b^8 , that normally project through the buffer-head and serve when such buffer-head is coupled to the buffer-head on an adjacent vehicle to enter recesses in the latter head and prevent rotary motion between the two. Fig. 12 shows a modified arrangement wherein the flexible connector b' for rotating the buffer-head is led around horizontal guide-pulleys b^9 and is or may be provided at one or at each side of the vehicle with a handle b^9 , by which the connector can be pulled laterally, as indicated in dotted lines, to rotate the buffer-head to a sufficient extent to move the horns c into their inoperative positions.

The buffer-rod a in each case may be made hollow, as and for the purpose hereinbefore described. Figs. 5 to 8 show a hollow buffer-rod the inner end of which is connected to a length of flexible piping 16 and the outer end of which is provided with a coupling device consisting in the example shown of a ring 17, of india rubber or other suitable flexible material, that is made of V-section and secured in place, as by a flanged bush 18, so that its interior is in connection with a passage 19 in the rod, the outer face of the coupling being adapted to make a close joint with another similar coupling device carried by the buffer-rod of an adjacent vehicle when the two vehicles are coupled together.

Figs. 13 and 14 illustrate an arrangement in which the hollow buffer-rod a is provided at its outer end b with three coupling devices 17, each in connection with a separate train-pipe 16, extending through and carried by the hollow buffer-rod a , and each adapted to make a close joint with another similar coupling device carried by the buffer-rod a of an adjacent vehicle when the two vehicles are coupled together. Each pipe may be provided with a valve, whereby it can be opened and closed either automatically or by hand when the pipes on adjacent vehicles are respectively coupled and uncoupled. Fig. 15 shows an arrangement for this purpose wherein the bush 18 is formed with a seat 20 for a valve 21, that is normally pressed against such seat to close the end of the pipe by a coiled spring 22 and is adapted to be forced from its seat against the action of the spring to open the pipe by the star-shaped head 23 of its stem 24 abutting against the head and stem of a similar valve on an adjacent vehicle.

Coupling, buffing, and draw-gear apparatus of the kind herein described may be arranged

at the center-line of the vehicle, or two sets of such apparatus may be used, arranged at opposite sides of the center-line of the vehicle.

What I claim is—

1. Combined coupling buffing and draw-gear apparatus for railway and similar vehicles, comprising a buffer-rod, means for carrying and supporting said rod in a normally-horizontal position on a vehicle but so that it can move in horizontal and vertical directions and also in an endwise direction, a buffer-plate carried by said rod, and combined centering and coupling devices carried by said rod and plate and arranged above and below said buffer-plate and so as to extend away from the end of the vehicle to which said apparatus is applied and to diverge from each other in both vertical and lateral senses when in their operative positions, said buffer-plate and devices being each capable of acting against and coöperating with similar parts of like apparatus on an adjacent vehicle to bring the two buffer-rods of the two apparatus into line, if they be not so, when the two vehicles are brought together, and said combined coupling and centering devices then acting to become automatically coupled to such second apparatus, substantially as described.

2. Combined coupling buffing and draw-gear apparatus for railway and similar vehicles, comprising a buffer-rod, means for carrying and supporting said rod in a normally-horizontal position on a vehicle but so that it can move in horizontal and vertical directions and also in an endwise direction, a buffer-plate carried by said rod, and adapted by contact with a similar buffer-plate on an adjacent vehicle to center the buffer and attached parts, combined centering and coupling devices carried by said rod and plate and arranged above and below said buffer-plate and so as to extend away from the end of the vehicle to which said apparatus is applied and to diverge from each other in both vertical and lateral senses when in their operative positions, and means for moving said combined centering and coupling devices into their inoperative position, substantially as described.

3. Combined coupling buffing and draw-gear apparatus for railway and similar vehicles, comprising a buffer-rod, means for carrying and supporting said rod in a normally-horizontal position on a vehicle but so that it can move in horizontal and vertical directions and also in an endwise direction, a buffer-plate carried by said buffer-rod, and adapted by contact with a similar buffer-plate on an adjacent vehicle to center the buffer-rod and attached parts, and a pair of coupling and centering horns that are carried by said buffer-rod, are arranged to project over and under said buffer-plate and to diverge from each other in both vertical and lateral senses when

in their operative positions and are then capable of forming combined centering and coupling devices, substantially as described.

4. Combined coupling buffing and draw-gear apparatus for railway and similar vehicles comprising a buffer-rod, means for carrying and supporting said rod in a normally-horizontal position on a vehicle but so that it can move in horizontal and vertical directions and also in an endwise direction, a buffer-plate carried by said buffer-rod, and adapted by contact with a similar buffer-plate on an adjacent vehicle to center the buffer-rod and attached parts, combined centering and coupling horns carried by said buffer-rod, arranged above and below said buffer-plate and to diverge from each other both vertically and laterally and each formed with a hook-like engaging part, and means whereby said horns can be moved into an operative or inoperative position at will, substantially as described.

5. Combined coupling buffing and draw-gear apparatus for railway and similar vehicles comprising a rotary buffer-rod, means for carrying and supporting said rod in a normally-horizontal position on a vehicle but so that it can move in horizontal and vertical directions and also in an endwise direction, and can also be partly rotated about its own axis, a buffer-plate carried by said buffer-rod, and adapted by contact with a similar buffer-plate on an adjacent vehicle to center the buffer-rod and attached parts, combined centering and coupling horns carried by said buffer-rod, arranged above and below said buffer-plate and to diverge from each other both vertically and laterally and each formed with a hook-like engaging part, and means whereby said buffer rod, plate and horns can be partly rotated about the axis of said rod, substantially as described for the purposes specified.

6. In combined coupling buffing and draw-gear apparatus for railway and similar vehicles, the combination of a rotary buffer-rod having a buffer-plate, adapted by contact with a similar buffer-plate on an adjacent vehicle to center the buffer-rod and attached parts, a pair of coupling and centering horns *c* carried by said rod and plate, arranged above and below said plate and to diverge from each other and formed with hook-like parts having abutment-surfaces *g*, means for supporting and carrying said rod in a normally-horizontal position but so that it can swivel in various directions and move endwise, and means capable of being operated from either side of the vehicle carrying said apparatus and of partly rotating said rod, plate and hooks, substantially as described for the purpose specified.

7. Combined coupling buffing and draw-gear apparatus for railway and similar vehicles comprising a buffer-rod, means for car-

rying and supporting said rod in a normally-horizontal position on a vehicle but so that it can move in horizontal and vertical directions and also in an endwise direction, a buffer-plate carried by said buffer-rod, and adapted by contact with a similar buffer-plate on an adjacent vehicle to center the buffer-rod and attached parts, vertically and laterally diverging horns *c* carried by said buffer rod and plate, arranged above and below the latter and having hook-like abutment-surfaces *g*, a holding device connected to said buffer-rod, buffer-plate and horns and adapted to be engaged with said carrying and supporting means in one or other of two positions corresponding to the operative and inoperative positions of said buffer-plate and horns, and means for operating said holding device and turning said buffer-plate and horns about the axis of said buffer-rod from either side of the vehicle, substantially as described.

8. In combined coupling buffing and draw-gear apparatus for railway and similar vehicles, the combination with a buffer-rod, a buffer-plate adapted by contact with a similar buffer-plate on an adjacent vehicle to center the buffer-rod, and combined centering and coupling devices carried thereby and extending over and under said buffer-plate, of means for carrying, supporting and controlling the movements of said buffer-rod and attached parts, said means comprising bearings through which said buffer-rod extends and against one of which said buffer-plate abuts, the inner of said bearings having an outwardly-flaring passage therethrough for said rod and being carried by the vehicle, one or more combined buffer and draw springs located between said bearings, an abutment device carried by the inner end of said buffer-rod and bearing against the inner end of said inner bearing, means for limiting the outward movement of the other bearing, and means adapted to normally hold said buffer-rod and attached parts in the mid or central position, substantially as described for the purposes specified.

9. In combined coupling buffing and draw-gear apparatus for railway and similar vehicles, the combination with a buffer-rod, buffer-head and combined centering and coupling devices carried thereby, of means for carrying, supporting and controlling the movements of said buffer-rod and attached parts, said means comprising inner and outer bearings through which said buffer-rod extends and against the outer of which said buffer-head abuts, said inner bearing having an outwardly-flaring hole therethrough for said rod, a combined buffer and draw spring located between said bearings and surrounding said rod, an abutment device carried by said rod and bearing against the inner end of said inner bearing, a third bearing arranged on the vehicle so as to turn about a vertical axis and

through which said inner bearing can slide endwise but cannot rotate, means connecting said outer bearing to said third bearing and adapted to allow of inward, outward and angular movements of said outer bearing, and a spring device adapted to normally hold said third bearing and attached parts in the mid or central position, substantially as described.

10. In combined coupling buffing and draw-gear apparatus for railway and similar vehicles, the combination of a buffer-rod, a buffer-head and combined centering and coupling devices carried by the outer end of said rod, an abutment device carried by the inner end 15 of said rod, inner and outer bearings through which said rod extends, against the outer of which said buffer-head abuts and against the inner of which said abutment bears, a coiled combined buffer and draw spring located between and connected at its ends to said inner and outer bearings and surrounding said buffer-rod, a third bearing through which said inner bearing can slide endwise but cannot rotate, means connecting said outer and third 20 bearings so as to allow of limited inward, outward and angular movements of said outer bearing, upper and lower bearings carried by the vehicle to which the apparatus is applied and in which said third bearing is mounted 25 to turn about a vertical axis, means adapted to normally hold or return said third bearing and attached parts in or to the mid or central position but capable of allowing said parts to move laterally, a pawl or catch mounted 30 on said buffer-head and adapted to be engaged with either of two different parts of said outer bearing, and means adapted to disengage said pawl or catch from one part of said outer bearing, to partly rotate the buffer- 35 head and horns about the axis of said buffer-rod, and to reengage said pawl or catch with another part of said outer bearing, substantially as described for the purposes specified.

40. In a railway or like vehicle, combined coupling buffing and draw-gear apparatus comprising the outer bearing *p* with recesses 45 14 and 15, the inner bearing *q* having a flaring hole therethrough, the bearing *w* in which said bearing *q* can slide endwise but cannot 50 rotate, upper and lower bearings carried by said vehicle and in which said bearing *w* is mounted to turn about a vertical axis, the tie-bolts 7 connecting said bearings *p* and *w* as described, the coiled spring 6 located between and connected at its ends to said bearings *p* and *q*, one or more springs controlling 55 the movements of said bearing *w* and attached parts, a buffer-rod extending through said bearings *p*, *q* and spring 6, a buffer-head fixed 60 to the outer end of said buffer-rod and acting against said bearing *p*, the diverging horns *c* carried by said buffer-head *b* and each formed with hook-like parts or shoulders *g*, an adjustable abutment carried by the inner 65 end of said buffer-rod and bearing against said bearing *q*, a catch 13 mounted on said

buffer-head *b* and adapted to enter either of the recesses 14 and 15 in said bearing *p*, and a handle *l* journaled in said buffer-head and to which said catch is fixed, substantially as 70 described.

12. In combined coupling buffing and draw-gear apparatus for railway and similar vehicles, a hollow buffer-rod provided with a buffer-plate having a flat outer surface and with 75 centering and coupling devices, means for carrying and supporting said rod in a normally-horizontal position on a vehicle but so that it can move in horizontal and vertical directions and also in an endwise direction, 80 a train-pipe extending from the inner end of said hollow buffer-rod, and a pipe-coupling device that is carried by and projects beyond the outer end of said buffer-plate, is in communication with said train-pipe, and is adapted to make a close joint 85 with an appropriate coupling device on the buffer-plate of an adjacent vehicle when the two vehicles carrying said devices are brought together, substantially as described for the 90 purpose specified.

13. In combined coupling buffing and draw-gear apparatus for railway and similar vehicles, a hollow buffer-rod provided with a buffer-head having a flat outer surface and with 95 centering and coupling devices, means for carrying and supporting said rod in a normally-horizontal position on a vehicle but so that it can move in horizontal and vertical directions and also in an endwise direction, 100 one or more train-pipes located within said hollow buffer-rod and extending from the inner end thereof, and one or more pipe-coupling devices carried by and projecting beyond the said buffer-plate, connected to the 105 outer end or ends of the train pipe or pipes and adapted to make a close joint with an appropriate coupling device or devices on the buffer-plate of an adjacent vehicle when the two vehicles carrying said devices are brought 110 together, substantially as described for the purpose specified.

14. In combined coupling buffing and draw-gear apparatus for railway and similar vehicles, a hollow buffer-rod provided with a buffer-plate having a flat outer surface, and with 115 centering and coupling devices arranged above and below said plate, means for carrying and supporting said rod in a normally-horizontal position on a vehicle but so that it can move 120 in horizontal and vertical directions and also in an endwise direction, a train-pipe extending from the inner end of said hollow buffer-rod, a pipe-coupling device that is carried by and projecting beyond the outer end of said buffer-plate, is in communication with said train-pipe, and is adapted to make a close joint 125 with an appropriate coupling device on an adjacent vehicle when the two vehicles carrying said devices are brought together, and a valve adapted to close the outlet from 130 said train-pipe when the corresponding pipe-

coupling device is disengaged from that on another vehicle and having an outwardly-projecting part whereby it can be automatically opened when said pipe-coupling device 5 becomes engaged with that on the second vehicle, substantially as described for the purposes specified.

Signed at 77 Cornhill, London, E. C., England, this 27th day of February, 1900.

SAMUEL GEOGHEGAN.
